UNITED STATES PATENT OFFICE

2,581,042

NAIL PACKAGING MACHINE

Stuart Otto, New York, N. Y.

Application August 17, 1946, Serial No. 691,266

8 Claims. (Cl. 10—162)

1

The present invention relates to a method and apparatus for packaging oblong magnetic objects such as nails, screws, bolts, pins, rivets, spikes and the like with said objects arranged in parallelism so as to utilize to the maximum all of the available space within the package or container.

While the apparatus described herein will also handle the packaging of metal powder, nuts, washers, short rivets and the like which may not be termed oblong objects, it will be hereinafter described specifically with reference to the packaging of nails. It is to be understood, however, that the specific description with reference to the packaging of nails is not intended as a limitation of the scope of this invention.

Machines have been designed heretofore for packaging nails wherein the nails are fed from a hopper or the like between the opposite poles of a magnet so as to orient them in substantial parallelism and wherein the nails so oriented are removed from the machine and packaged in suitable containers. All of the machines heretofore designed, however, require constant attention and operation by an experienced operator and are by no means automatic.

One object of the present invention is to provide apparatus for automatically packaging weighed quantities of nails without requiring manual operation or adjustment of the machine from the time that the apparatus is set to handle nails of a given size.

Another object of the present invention is to provide a machine that will, with great accuracy, orient and package only a predetermined weight of nails in any one package.

A further object is to provide a method and apparatus wherein nails are packed into a package while the nails are maintained in substantial parallelism under the influence of parallel lines of magnetic force.

Still another object of the present invention is to provide a machine having means for conveying empty containers or packages to the machine, filling them with nails oriented in parallelism and removing them from the machine.

These and other objects will become apparent from the description that follows hereinafter.

The apparatus herein described is capable of packing nails into packages in either single tiers or in a multiple of tiers, i. e., nails may be packed into a small carton or box which is substantially of the same length as the length of the nails, or the nails may be packed into containers of substantially greater length than the nails so that

2

two, three, four or more lengths of nails may be packed into the same package.

When nails are packaged while they are in substantial parallelism, the saving in volume of packages for a given weight of nails varies from 20% for short flathead nails to as much as 60% for some types of long thin nails and generally averages about 35 to 40 per cent.

The term "container," as used in the present specification and appended claims, is intended to include receptacles and vessels such as boxes, cartons, crates, kegs, sacks, bags and the like generally employed to contain, ship and store nails in quantity for industrial, wholesale or retail purposes.

In carrying out the present invention, nails are taken from any suitable source to a weighing mechanism by means of a conveyor provided beneath the lip thereof with a magnetizable dribble arrestor. When a predetermined mass of nails has been deposited in the weighing mechanism, movement of the conveyor is stopped, the dribble arrestor is actuated, and the nails in the weighing mechanism are deposited in a vibrating hopper to bounce and thereby separate the nails from one another. The separated nails are then permitted to fall into a magnetic field between the poles of a magnet where the lines of force are parallel. In this magnetic field the nails come to rest in parallelism but somewhat spaced apart. A plunger is provided to pack the nails into the package that may be brought into position by an intermittently moving conveyor and to remove the filled package from the magnetic field. The filled package may thereupon be conveyed away from the machine for the usual processing prior to shipment.

Reference is now made to the accompanying drawings in which:

Figure 1 is a view in perspective of an embodiment of the present invention designed to pack nails into packages such as cartons moving along two parallel conveyors;

Figure 2 is a view in perspective of another embodiment designed to pack several tiers of nails into single packages;

Figure 3 is a view in perspective of still another embodiment of the present invention designed to pack simultaneously single tiers of nails of the same or different sizes into individual packages;

Figure 4 is a part-sectional elevation of an embodiment designed to pack nails into packages such as kegs, of circular cross section;

Figure 5 is a part-sectional plan view of the

embodiment shown in Figure 7 designed initially to pack four tiers of nails into a keg;

Figure 6 is a diagrammatic view showing a method of packing two tiers of nails into a keg;

Figure 7 is a similar view illustrating a method of packing three tiers of nails into a keg;

Figure 8 is a schematic view illustrating mechanism for coordinating the movements of some of the moving parts shown in Figure 1;

Figure 9 is a schematic view illustrating mechanical and electrical means for coordinating the movements of the remaining moving parts shown in Figure 1; and

Figure 10 is a part-sectional elevation illustrating a mechanism for adjusting the distance between the north and south poles of an electromagnet.

The apparatus illustrated in Figure 1 includes two poles 11 and 12 of an electro-magnet supported upon a cut-out, non-magnetic bed plate 10 as shown more clearly in Figure 10. Pole 11 is fixed to bed plate 10 by brackets such as angle irons 13 while pole 12 is slidably mounted on bed plate 10 by any suitable means such as angle irons 14. A magnetic field having parallel lines of force between poles 11 and 12 is induced by means of a coil 15 about a telescopic core 16. The distance between poles 11 and 12 may be adjusted by turning hand wheel 17 of threaded shaft 18 mounted for threaded engagement in block 19 affixed to bed plate 10. Shaft 18 has a flanged end 18a in engagement with an annular recess in or affixed to, pole 12.

It is within the contemplation of this invention, however, to make both poles 11 and 12 movable relative to bed plate 10.

An H-shaped chamber 20 of hard, smooth, non-magnetic material comprising two vertical chutes 21 and 22 and a rectangular section 24, having side walls 26 and 27 and a closed bottom 29 and communicating through openings in the ends thereof with vertical chutes 21 and 22, is locked into position between magnetic poles 11 and 12. An inverted L-shaped wiper plate 30, likewise of hard, smooth, non-magnetic material, is partly disposed within section 24 and adapted to move from end to end thereof by means of screw drive 31 driven by clutch 32. A vibrating hopper 34 is provided to bounce, separate and drop nails 36 into section 24 of chamber 20 and a pair of plungers 37, actuated by plunger rods 39, are provided within chutes 21 and 22.

Beneath bed plate 10 there are provided two conveyors 40 and 41 to convey cartons 42 to positions beneath chutes 21 and 22 and onto elevator platforms 44 and 46 actuated by elevator plungers 47 and 49, respectively.

In operation, a measured mass of nails 36 is fed into section 24 by way of vibrating hopper 34. The magnetic lines of force generated by magnetic poles 11 and 12 and passing through section 24 orient the nails into substantial parallelism. As soon as all the nails have been deposited in section 24, clutch 32 is thrown to turn screw 31 so as to move L-shaped wiper plate 30 to the position indicated by reference numeral 30', so that the loosely packed, oriented nails in section 24 are pushed into chute 21 and said chute becomes a closed shaft, open only at the bottom. Elevator plunger 47 actuates elevator platform 44 to raise carton 42 so that the lower end 50 of chute 21 moves relatively into carton 42 until it touches the bottom of said carton and assumes the position shown in the right hand portion of Figure 1 with reference to chute 22, elevator

platform 46, and elevator plunger rod 49. Plunger rod 39 then moves plunger 37 down through chute 21 to pack the nails into carton 42 and continues its downward stroke through chute 21 until it has depressed elevator platform 44 and carton 42, which is now filled with nails, to a position flush with conveyor 40. Plunger 37 then moves upwardly and conveyor 40 moves carton 42 onward so that the carton can be covered and further processed for shipment. In the meantime, and during the downward stroke of plunger 37, a further measured mass of nails is fed into section 24 as before. Clutch 32 operates screw shaft 31 in the opposite direction to move plate 30 to the right to push the oriented nails into and close chute 22. The operation of packing the nails in chute 22 into carton 42 on elevator platform 46 is accomplished by plunger 37 in exactly the same manner as described with reference to the container on elevator platform 44.

The interior dimension of section 24 between walls 26 and 27, and the corresponding dimensions within chutes 21 and 22, are slightly in excess of the length of the nails to be packaged. When it is desired to adjust the machine to handle a different size of nail, chamber 20 is removed and a similar chamber having interior dimensions corresponding to the new length of the nails to be packed is locked in place. Magnetic pole 12 can be moved backwards or forwards by means of hand wheel 17 to accommodate the different sizes of chamber 20. A new set of plungers 37 corresponding in size with the interior dimensions of the chutes in the new chamber are attached to plunger rods 39 and cartons 42 are replaced by cartons adapted to fit around ends 50 of the new chutes. Part 30 is changed accordingly.

The embodiment illustrated in Figure 2 is suitable for packaging four tiers of nails into a single package. This modification includes an elevator platform 60 actuated by elevator shafts 61 for lifting a package 62 from a conveyor (not shown) to a position about the lower end of a rectangular chamber 64 provided with three vertical partitions 66, 67 and 68, indicated by dotted lines, to divide chamber 64 into four equal parts. An electro-magnet comprising a coil 69 and two arms 70 and 71 at opposite ends of chamber 64 further provided with auxiliary poles pieces 72 and 74 generates parallel lines of magnetic force through chamber 64. Nails are fed from any suitable source (not shown) onto conveyors 75, over an electro-magnetic dribble arrestor 76 and onto one or a series of weighing mechanisms 77. When predetermined masses of nails have been deposited on weighing mechanisms 77, they operate to interrupt the motion of conveyor 75 and to activate dribble arrestor 76 so that any nails that have left the lips of conveyors 75 and not yet reached weighing mechanisms 77 will be attracted and held to dribble arrestor 76. This may, for example, be accomplished by electrical or other suitable means, as hereinafter described. The nails on weighing mechanisms 77 are then dumped into vibrating chutes or hoppers 79 and passed into the respective compartments in chamber 64 wherein they are oriented in substantial parallelism by the action of the magnetic lines of force. When the measured masses of nails have been deposited in the various compartments of chamber 64, plungers 80, activated by plunger rods 39, push the nails down into package 62 and push the

entire filled package and elevator platform 60 down onto the conveyor, whereupon package 62 is removed from elevator platform 60 and replaced by an empty package.

It is, of course, within the contemplation of this invention to provide either a single conveyor and weighing mechanism combination for all of the compartments, in which event said combination will be shifted progressively to discharge a measured mass of nails into each hopper, or to provide such a combination for each hopper, as shown in Figure 2, whereby the various compartments will be filled simultaneously. Furthermore, it is within the scope of this invention to divide chamber 64 into compartments of different sizes to permit the simultaneous packaging of two or more different sizes of nails into a single package.

When it is desired to adapt the machine illustrated in Figure 2 for packaging a different size of nail, chamber 64 and chutes 79 are replaced by a new chamber 64 provided with hoppers or chutes 79 of convenient size and plungers 80 are detached from rods 39 so that a new set of plungers may be attached to plunger rods 39. Finally the auxiliary pole pieces 72 and 74 are replaced by pieces of sufficient thickness to take up the space between permanent pole pieces 73 and 71 and the end of chamber 64, leaving sufficient room to allow a package 62 to be elevated to the position shown.

The embodiment illustrated in Figure 3 is one designed especially to pack and fill simultaneously a number of cartons with nails. This machine includes a coil 69, magnetic pole pieces 70 and 71, and auxiliary pole pieces 72 and 74 take up the space between permanent pole pieces 70 and 71 and the ends of a series of chambers 81, or it may be made at right angles to that shown in Figure 3 so that there is only one length of nail between the poles instead of 3. An elevator platform 60 actuated by elevator plunger rods 64 operates to lift eight empty cartons 82 into juxtaposition at the bottom of chambers 81 and a series of vibrating hoppers 79 similar to that of the embodiment shown in Figure 2, furnished with suitable weighing mechanisms, dribble arrestors and conveyors (not shown), are provided for the introduction of nails into the magnetic field induced by pole pieces 70, 72, 71 and 74 and passing through chambers 81. When the required mass of nails has been deposited in each of said chambers, plungers 84 actuated by plunger rods 39 operate to pack the nails into cartons 82 and to depress elevator platform 60 until it is again flush with the conveyor (not shown), so that filled cartons 82 can be moved away and replaced by empty cartons.

The principle of operation of a nail packaging machine designed to pack nails into a container of circular cross-section, such as a keg or barrel is the same as that of the machines illustrated in Figures 1 to 3. A machine designed specifically for this purpose is shown diagrammatically in Figures 4 and 5 wherein a hopper 90 caused to vibrate by means of vibrating mechanism 91 intermittently deposits predetermined masses of separated nails into a chute-like chamber 92 having its bottom closed by the bottom 94 of a keg 96 supported between poles 97 and 99 by an elevator or platform 100. Poles 97 and 99 may be the poles of an electro-magnet provided with a coil 101. Chamber 92 may be of circular or rectangular cross-section to fit within keg 96 and

it may be divided lengthwise into a plurality of compartments such as shown by way of example in Figures 5, 6, and 7 to accommodate given sizes of nails. If 92 is cylindrical then there can be no partition subdividing it into compartments.

- When a predetermined mass of nails has been deposited in chamber 92 and oriented in substantial parallelism along the lines of force between poles 97 and 99, plunger 102 moves downwardly through chamber 92 to pack the nails into keg 96 and, if desired, to depress filled keg 96 until elevator platform 100 assumes a position flush with a conveyor (not shown in Figure 4) so as to make possible the removal of the filled keg and its replacement by an empty keg. Plunger 102 is interchangeable with others of different sizes and shapes to fit different chambers 92. Elevator platform 100 may be provided with a vibrator 104 to assist in filling with nails the space between the side wall of keg 96 and the side wall or walls of chamber 92 when keg 96 is depressed from proximity with chamber 92.

- The movement in timed relation of the various moving parts of the apparatus shown in Figure 1 is illustrated by way of example in Figures 8 and 9. A motor 110 is connected by suitable gears and shafts to cranks 111 and 112, clutch drive 32 and ring gear 114. Cranks 111 and 112, in cooperation with coil springs 116 and 117 operate to raise and lower resiliently, and in timed relation, elevator plungers 47 and 48 carrying elevator platform 44 and 46, respectively. Ring gear 114 operates through clutches 119 and 120 to actuate plunger rods 39 by means of cranks 121 and 122, likewise in timed relation. A rod 124 engaged with a shifting lever 126 for clutch 32 and carrying a pair of cam rollers 127 and 129, a pair of lugs 130 and 131, and a switch 132 is positioned across the face of the machine. A pair of pawls 134 and 136 pivoted at pivot points 137 and 138, engageable with a slot in a projecting extension 135 of wiper plate 30 are normally held in the up position in which pawl 136 is shown by springs (not shown) acting on rods 139 and 140 in engagement with clutches 119 and 120 respectively. Plunger rods 39 are provided with cam extensions 141 and 142 and, when not actuated by cranks 121 or 122 through clutches 119 or 120, are held in the up position by springs 144 and 146.

- Weighing mechanism 77 is provided with a number of contact points 147, 148 and 149, mounted on conductor ring 150 and capable of successively making electrical contact with contact point 151 on line 152 to close the circuit with line 154, and an electrically released spring lock 156 by switch 132. Lines 152 and 154 are connected to a solenoid 159 which in turn is operatively connected to an electro-magnet 160 for dribble arrestor 76 and to vibrator 161 for conveyor 75. A vibrator 91 for vibrating hopper 34 may be connected directly to the line to maintain constant vibration of the hopper.

- In operation, rod 124 is normally in the neutral position shown in Figure 8. When wiper plate 30 reaches its extreme left position, plate extension 135 comes into contact with lug 130 on rod 124 to move rod 124 to the left until it assumes the neutral position shown to disengage screw 31 from clutch 32 and to disengage switch 132 from its electrical contacts. In moving to its extreme left position, extension 135 also presses down pawl 134 to engage crank 121 with clutch 119, thus commencing the working stroke of left plunger 37. In the course of the downward

stroke of plunger 37 through chute 21, cam extension 141 bears against cam roller 127 and causes rod 124 to move to its extreme left position so that screw 31 becomes engaged with clutch 32 to move wiper plate 30 to the right and switch 132 closes the circuit to bring about the momentary unlocking of lock 156.

In the meantime conveyor 75 is operative and dribble arrestor magnet 160 is deenergized, to feed nails from any suitable source into weighing mechanism 77 by way of conveyor 75, the position of said weighing mechanism being that shown in the drawing whereby contact is made between contact points 149 and 151 to close the circuit to solenoid 159. As soon as a predetermined mass of nails has been deposited in weighing mechanism 77, it rotates through a slight angle insufficient to dump the nails into vibrating hopper 34 but sufficient to open the circuit to solenoid 159 and thus to interrupt operation of conveyor 75 and to energize electro-magnet 160 of dribble arrestor 76. The subsequent opening of lock 156 permits weighing mechanism 77 to rotate sufficiently to dump the nails into hopper 34, again assume a receiving position for the nails, and close the circuit between contact points 148 and 151 to energize solenoid 159 and in turn deenergize dribble arrestor 76 and activate conveyor 75.

When wiper plate 30 has moved a sufficient distance to the right to disengage pawl 134, rod 139 moves upwardly to disengage crank 121 from clutch 119. Plunger 37 is then drawn upwardly through chute 21 to its rest position by means of spring 144.

When wiper plate 30 reaches its extreme right position, extension 135 engages lug 131 to disengage screw 31 from clutch 32 and depresses pawl 136 to start the working stroke of plunger rod 39 as before. Cam 142 engages cam roller 129 to move rod to its extreme right position to reengage screw 31 for reverse drive through clutch 32 and switch 132 again closes the circuit to momentarily release lock 156. The operations are the same as those previously described when wiper plate 30 moves to the left to close chute 21.

It is to be understood, of course, that similar coordinating means are applicable, with considerable simplification due to the lesser number of moving parts, to the embodiments illustrated in Figures 2, 3 and 4.

Chambers such as H-shaped chamber 20 and chambers 64, 81, and 92 may be made of any smooth, non-magnetic material capable of withstanding the continued impact and abrasion of the nails passing therethrough. It has been found, however, that the preferable construction is to make each chamber of one integral welded piece of non-magnetic, stainless steel with a polished interior surface in order to facilitate the pushing of the nails by wiper plate 30 and plungers 37 of Figure 1 or plungers 80, 84 and 102 of Figures 2, 3 and 4. Plate 30 and plungers 37, 80, 84 and 102 should likewise be of a hard non-magnetic material such as brass or stainless steel and their surfaces should be polished smooth.

It is within the scope of this invention to use either permanent magnets or electro-magnets to generate the magnetic field. It will be understood, of course, that in some cases electro-magnets are required to provide a sufficiently dense magnetic flux when large quantities of articles are being packaged, for example in kegs or barrels. When permanent magnets or electro-mag-

nets energized continuously throughout the packaging operation are employed, it is desirable that the plunger or plungers used to pack the nails into the packages be operated as described to push the filled packages beyond the effective magnetic field to avoid disarranging the orientation of the nails therein under the influence of the curved lines of force remote from the magnetic poles. When electro-magnets are energized only periodically, that is, energized to orient the nails in parallelism in the chamber and de-energized during operation of the plunger or plungers, the nails must be pushed rapidly into the package so that no opportunity is allowed them to fall freely or otherwise get out of parallelism before they are packaged. The strength of the magnetic field required to orient the nails in parallelism varies with the size and quantity of nails to be packaged and can readily be determined by trial and error.

It is manifest that the apparatus herein described, with the magnetic poles removed or de-energized, is likewise capable of packing accurately weighed quantities of metallic articles, such as metal powders, nuts, washers, short rivets and the like that do not require parallel alignment when packed.

It is obvious that many changes may be made in the construction of the apparatus illustrated without departing from the spirit and scope of this invention, as defined in the appended claims.

I claim:

1. A nail packaging machine comprising an H-shaped chamber of non-magnetic material having a central, rectangular section and two vertical chute sections, said central section being open at the top to receive a deposit of nails and open at the ends for communicating with each of said chute sections, said chute sections being closeable at the bottom by a container for receiving said nails, magnetic poles of opposite polarity adjacent said chamber to generate a magnetic field of sufficient strength to orient nails within said chamber in substantial parallelism, means for transferring said nails from said central section alternately to one of said chute sections, and plunger means within said chute section to pack nails within said chute section into said container.

2. A nail packaging machine comprising a chamber of non-magnetic material to receive nails, magnetic poles of opposite polarity adjacent to and at opposite sides of said chamber to generate parallel lines of force through said chamber, a conveyor to move a container into position below the chamber, means to elevate the container to a position contiguous with the lower portion of the chamber, means for introducing a premeasured mass of nails into the chamber for orientation thereof along said parallel lines of force, plunger means to transfer the nails oriented in parallelism into said container and to depress said container and said elevating means to a position flush with said conveyor and means for operating said nail introducing means, conveyor, elevating means, and plunger means in timed relationship.

3. A nail packaging machine comprising a chamber of non-magnetic material to receive a predetermined mass of nails, magnetic poles of opposite polarity adjacent to and at opposite sides of said chamber to generate parallel lines of force through said chamber, a conveyor to move a container into position below the chamber, an elevator to elevate the container to a

position contiguous with the lower portion of the chamber, means for introducing a premeasured mass of nails into the chamber for orientation thereof along said parallel lines of force, a plunger to transfer the nails oriented in parallelism from said chamber into said container and to depress the container and the elevator to a position flush with the conveyor and outside the effective field of the magnetic lines of force generated by said magnetic poles and means for operating said nail introducing means, conveyor, elevator, and plunger in timed relationship.

4. A nail packaging machine comprising a rectangular chamber having side and end walls of non-magnetic material and being open at the bottom, magnetic poles of opposite polarity adjacent to and at opposite sides of said chamber to generate parallel lines of force through said chamber, a conveyor to move a container into position below the chamber, means to elevate the container to close the bottom of the chamber, means for depositing in said chamber a premeasured mass of nails for orientation within said chamber along said parallel lines of force, plunger means to transfer the nails oriented in parallelism into said container and to depress said container and said elevating means to a position flush with said conveyor and means for operating said depositing means, conveyor, elevating means, and plunger means in timed relationship.

5. A nail packaging machine comprising a rectangular chamber having side and end walls of non-magnetic material and being open at the bottom, magnetic poles of opposite polarity adjacent to and at opposite sides of said chamber to generate parallel lines of force through said chamber, a conveyor to move a container into position below the chamber, an elevator to elevate the container to a position contiguous with the lower portion of the chamber, means for depositing in said chamber a premeasured mass of nails for orientation within said chamber along said parallel lines of force, a plunger to transfer the nails oriented in parallelism from said chamber into said container and to depress the container and the elevator to a position flush with the conveyor and outside the effective field of the magnetic lines of force generated by said magnetic poles and means for operating said depositing means, conveyor, elevator, and plunger in timed relationship.

6. A nail packaging machine comprising an H-shaped chamber of non-magnetic material having a central rectangular section and two vertical chute sections, said central section being open at the top to receive a predetermined mass of nails and open at the ends for communicating with said chute sections, said chute sections being open at the bottom, magnetic poles of opposite polarity adjacent to and at opposite sides of said chamber to generate parallel lines of force through said chamber, conveyors to move containers successively into position below said chute sections, elevators to elevate the containers to close the bottoms of said chute sections, means for intermittently introducing premeasured masses of nails into the central section of the chamber to orient said nails into substantial parallelism, a plate extending into and movable laterally through the central section of said chamber from end to end to transfer the nails oriented in parallelism within said section al-

ternately into said chute sections, plungers movable alternately and vertically through said chute sections to transfer the nails therein into the containers thereunder and to depress said containers and said elevators to positions flush with said conveyors, and means for operating said nail introducing means, said plate, said conveyors, said elevators and said plungers in timed relationship.

7. A nail packaging machine comprising an intermittently movable conveyor to move a container, a chamber having side walls of non-magnetic material, an opening to receive a predetermined mass of nails and an open bottom closeable by said container, magnetic poles of opposite polarity adjacent to and at opposite sides of said chamber to generate parallel lines of force through said chamber, an elevator to elevate the container from said conveyor to close the bottom of the chamber, means for introducing a premeasured mass of nails into the chamber for orientation thereof along said parallel lines of force, a plunger to pack the nails oriented in parallelism within said chamber into said container and to depress said container and the elevator to a position flush with the conveyor and means for operating said nail introducing means, said conveyor, said elevator and said plunger in timed relationship.

8. A nail packaging machine comprising an intermittently movable conveyor to move a container, an H-shaped chamber of non-magnetic material comprising a central rectangular section and two vertical chute sections, said central section being open at the top to receive a predetermined mass of nails and open at the ends for communicating with said chute sections, said chute sections being open at the bottom and individually closeable by said container, magnetic poles of opposite polarity adjacent to and at opposite sides of said chamber to generate parallel lines of force through said chamber, an elevator to elevate the container from said conveyor to close the bottom of one of said chute sections, means for introducing a premeasured mass of nails into the central section of the chamber to orient said nails into substantial parallelism, a plate extending into and movable laterally through the central section of said chamber from end to end to transfer the nails oriented in parallelism within said section into said one of said chute sections, a plunger to pack the nails oriented in parallelism within said chute section into said container and to depress said container and the elevator to a position flush with the conveyor, and means for operating said nail introducing means, said plate, said conveyor, said elevator and said plunger in timed relationship.

STUART OTTO.
